UNITED STATES PATENT OFFICE.

JOSEPH ROY RAMSEY, OF LYKENS, PENNSYLVANIA.

TURBINE-BLOWER.

1,205,016.

Specification of Letters Patent. Patented Nov. 14, 1916.

Application filed July 22, 1915. Serial No. 41,289.

To all whom it may concern:

Be it known that I, JOSEPH ROY RAMSEY, a citizen of the United States, residing at Lykens, in the county of Dauphin and State 5 of Pennsylvania, have invented certain new and useful Improvements in Turbine-Blowers, of which the following is a specification.

The present invention relates to improvements in turbine blowers especially adapted 10 for producing undergrate draft for furnaces, the apparatus, however, being susceptible of use wherever an artificial current of air under pressure is desired.

The primary object of the device is to 15 provide a very light construction which enables the highest efficiency in performing its draft function as well as insuring economy in manufacture.

To this end the invention consists of a 20 rotor or rotatable fan member for producing the air current, said fan member carrying peripheral impact or turbine blades arranged in spaced series and surrounded by an annular casing provided with stationary 25 blades lying intermediate the series aforesaid, the blades receiving impulse from a pressure medium introduced into the casing above mentioned.

For a full understanding of the present 30 invention, reference is to be had to the following description and the accompanying drawings, in which:

Figure 1 is a longitudinal sectional view 35 through an apparatus forming the embodiment of my invention. Fig. 2 is a front elevation thereof, a portion of the annular casing being broken away and shown in section. Fig. 3 is a vertical sectional view taken approximately on the line 3—3 of 40 Fig. 1, portions being broken away. Fig. 4 is a horizontal sectional view on the line 4—4 of Fig. 1. Fig. 5 is a sectional view taken approximately on the line 5—5 of Fig. 2.

Throughout the following description and on the several figures of the drawings, similar parts are referred to by like reference characters.

Referring to the drawings, the numeral 1 50 indicates a casing or passage leading to a furnace grate, said passage being located as usual in a wall 2. At the mouth of the casing 1 is disposed the improvements forming the subject matter of this invention, which 55 include the rotor 3 consisting of the fan blades 4 attached to the hub 5 which is car-

ried by the spindle 6. Surrounding the fan blades 4 is an annular ring 7 and upon said ring are provided two annular rows or series of impact blades 8, 8'. These outer and 60 inner series of blades are similar in formation, being substantially semicircular in cross section, the rows being arranged in spaced relation to each other as best disclosed by Fig. 1 of the drawings. The spindle 6, upon which the rotor revolves, has its outer bearing in a vertically disposed bracket 9, and this bracket is formed with an annular casing 10 which surrounds the ring 7 and its impact blades 8, 8' hereinbefore 65 mentioned. The bracket and casing are preferably attached to the mouth of the passage or conduit, as by means of the bolts 11 above and below said conduit. At the inner end, the spindle 6 is supported by a horizontal 70 bar 12, said bar being attached to the spindle by the nut 13 carried by the inner end of the spindle. The bar 12 is slidably received in offset recesses 14 at diametrically opposite points of the conduit 1, as clearly shown in 75 Fig. 4 of the drawings. It will be noted that the casing 10 at the top is formed, at one side, with a nozzle casing 15 to which the steam pipe 16 leads, said pipe preferably having a main throttle valve 17 for controlling admission of the pressure medium into 80 the nozzle casing. This nozzle casing has steam ports 18 arranged to direct the steam against the impact blades located directly opposite said ports, whereby impulse is 85 imparted to the rotor as will be readily appreciated by those skilled in the art to which this invention refers. An independent valve control 17' is provided for each of said ports, whereby full pressure at all or any one 90 of the ports may be obtained according to requirements.

An especial feature of my invention is the provision of stationary impact blades which are formed on the annular casing 10 100 projecting inwardly therefrom into the space between the annular impact blades carried by the rotor, said stationary blades being designated 19. Furthermore, these blades are of similar form to the impact 105 blades 8 and 8', excepting that they are reversely arranged or positioned with respect to said movable blades. It will be noted in Fig. 3, that the stationary blades 19 extend only the length of the nozzle 110 casing 15.

It will be understood from the foregoing

description that the steam admitted through the ports 18 will act against the outer row or series of impact blades 8, then against the stationary blades 19 formed on the annular casing 10, and finally impacting against the second series or inner row of impact blades 8', thus affording a double impulse to the rotor before final exhausting from the casing through the exhaust passage 10 20 leading from the bottom of the casing into the conduit 1.

To provide adequate lubrication for the rotor, which it will be understood, revolves at high speed, a suitable oil or lubricant 15 cup 21 is located adjacent to the device from which a pipe 22 leads to the spindle 6 which latter is hollow a greater portion of its length to convey the lubricant into the hub 5 of the rotor, the spindle being provided 20 with a plurality of openings 23 for this purpose. The lower portion of the hollow hub is generally filled with the lubricant so that the bearings 24 will be amply supplied.

25 Having thus described my invention, what I claim as new is:

1. In a device of the class described, the combination with a conduit having its end flanged outwardly, of a turbine blower comprising an annular casing of a diameter 30 larger than the diameter of the conduit, means for attaching the casing against the face of the flanged end of the conduit, said

flanged end thereby forming a side of the annular casing, a fan arranged at the mouth 35 of the conduit, a peripheral rim on said fan of a diameter substantially corresponding to the diameter of the conduit whereby to coöperate with the sides of the casing to form a closure therefor, spaced rows of impact blades on the rim of the fan, a series of stationary impact blades on the casing projecting into the space between the impact blades of the fan, and a nozzle arranged laterally of the casing for directing impelling fluid against the blades aforesaid. 45

2. In a turbine blower of the class described, the combination of a rotary fan, a conduit at the mouth of which said fan is disposed, an outer bracket member in which the fan is supported at one side, an annular casing formed on said bracket, means connecting said bracket and casing to the conduit, a nozzle casing located at one side of said annular casing, impulse members arranged on the periphery of said fan against which a pressure medium from the nozzle impinges, and an inner supporting member for said fan having slidable interlocking connection with the conduit, said conduit being 60 formed with an exhaust passage leading from the annular casing aforesaid and with lateral recesses to receive the inner supporting member aforesaid.

In testimony whereof I affix my signature. 65
JOSEPH ROY RAMSEY.
